UNITED STATES PATENT OFFICE.

JOSEPH BRAINARD CRESSLER, OF NORFOLK, VIRGINIA.

TORPEDO-GUARD.

1,267,383.

Specification of Letters Patent. Patented May 28, 1918.

Application filed August 24, 1917. Serial No. 187,995.

To all whom it may concern:

Be it known that I, JOSEPH BRAINARD CRESSLER, a citizen of the United States, residing at Norfolk, in the county of Norfolk 5 and State of Virginia, have invented a certain new and useful Improvement in Torpedo-Guards, of which the following is a full, clear, and exact description.

The object of this invention is to provide 10 means by which ships may be protected against the attacks of torpedoes, and the torpedoes recovered if desired.

The invention consists of a torpedo guard adapted to be attached to the sides of a ship, 15 and having an inclined member above which is arranged a substantially horizontal member provided with a series of cushions between which and the inclined member there are spaces of varying height to accommodate 20 date torpedoes of different diameter, the cushions affording sufficient resistance to hold the torpedo or capture it so that it may be recovered if desired; the guard being supported in an adjustable way so that it may 25 be properly located in the water, in accordance with the draft of the ship, and also being so mounted as to be capable of being let down into the water as desired, and of being raised up out of the water and then 30 turned up alongside the ship when not in use, as I will proceed now to explain and finally claim.

In the accompanying drawings illustrating the invention, in the several figures of 35 which like parts are similarly designated, Figure 1 is a top plan view showing one form of the invention applied to a ship. Fig. 2 is an end elevation with parts of the guard in section. Fig. 3 is a longitudinal 40 section of the support, drawn on a larger scale. Fig. 4 is a perspective view of a portion of one of the cushions.

The means for securing the guard on the sides of a ship may be of a variety of constructions, and are not shown herein, and so 45 also the means for raising and lowering the guard may be of a variety of constructions, and similarly are not shown herein.

Referring to Fig. 1, the ship is designated 50 1, and the guards designated 2, and the guard supports, of which only two for each guard are shown, are designated 3.

Each guard comprises the inclined member 4, which may be of any suitable construction and material, solid or of open work, 55 and provided on its outer edge with a

buoyant or other member 5, such as an air chamber. 6 are brackets rigidly fixed to the member 4, in a substantially horizontal plane, and having arranged on their underside a series of cushions 7 preferably extending therefrom to different depths or otherwise arranged so that the spaces between the several cushions and the member 4 will be of different heights to arrest torpedoes 60 of different diameter driven in between the member 4 and these cushions. These cushions should have such resistance affording characteristics as to serve to trap or hold the torpedoes, thus not only preventing them 65 from striking the ship but also serving to capture them and permit their recovery. One construction of cushions comprises a section of tubular material 8, such as hose, filled with air under pressure, and having 70 their ends closed by plugs 9, or otherwise, and covered with a defensive cover 10 of metal or other suitable material, which serves also as a holder for the air-containing 75 tube on the brackets 6, and also as a means 80 for preserving the rigidity of the tube without impairing its cushioning effect. Any number of these cushions may be used on the brackets.

The inclined member 4 preferably has applied to its inboard end a fender rod 11 extending longitudinally thereof and projecting into the space between such member 4 and the cushion member to close the space 85 against the passage of any torpedo that may 90 escape the innermost cushion.

As already indicated, suitable supports adapted to be applied to the sides of the vessel may be employed and I have herein shown one such comprising a back-piece 12 95 slotted longitudinally at 13, and having the head 14 arranged substantially at right angles thereto. On this back-piece is arranged a slide 15 adjustably secured to it by means of bolts and nuts 16 or other suitable devices, and provided with a head 17 in which is arranged a screw 18 extending up through the head 14 and provided with a hand-wheel or other operating device 19 by which the screw may be turned so as to raise and lower 100 the slide. 20 is a supporting angle hinged at 21 to the slide 15, and to which the inclined member 4 is rigidly fixed. The portion 22 of the supporting angle may extend out from the ship to any desired length 105 110 so as to provide for the location of the guard at a proper defensive distance from the side

of the ship. The hinge 21 admits of the raising of the guard against the side of the ship when not in use; and as already stated, any suitable means may be used for so raising the guard and holding it when so raised. The adjustability of the guard supports admits of the proper location of the guard in the water in accordance with the draft of the ship.

10 Fig. 2 in addition to showing the construction hereinabove described, shows also an auxiliary guard 23 which may be used, same consisting of a plate, net or other suitable means adapted to be suspended at the outboard edge of the member 4.

15 The guard supports will be such that when the guard is folded up against the side of the vessel, it will not materially obstruct the view from the deck. These supports will be made in such way as to locate the guard at the proper distance relative to the ship both when in the water and out of it.

20 Details of construction are variable within the principle of the invention as herein-25 after claimed.

What I claim is:—

1. A torpedo guard for ships, comprising a guard member supported at an incline, and a cushion member rigidly attached to and 30 overlying the inclined member substantially horizontally, with its cushions facing the top of the inclined member.

35 2. A torpedo guard for ships, comprising

a substantially rigid inclined member, and a substantially rigid cushion member fixed to 35 the inclined member and overlying the same in a substantially horizontal direction and thereby providing a series of spaces of different heights between the two in order to arrest torpedoes of different diameter.

40 3. A torpedo guard for ships, comprising a substantially rigid inclined member, a substantially rigid cushion member fixed to the inclined member and overlying the same 45 in a substantially horizontal direction and thereby providing a series of spaces of different heights between the two in order to arrest torpedoes of different diameter, and a longitudinally disposed fender interposed 50 between the inclined member and the cushion member at the most contracted space between the two.

4. A torpedo guard for ships, comprising a guard member supported at an incline, a cushion member rigidly attached to and 55 overlying the inclined member substantially horizontally, with its cushions facing the top of the inclined member and an auxiliary guard suspended from the outboard end of the inclined member.

50 In testimony whereof I have hereunto set my hand this 24th day of August A. D. 1917.

JOSEPH BRAINARD CRESSLER.
